CLAIM

The ornamental design for an electronic time lock for
vault doors and the like, as shown and described.

DESCRIPTION

FIG. 1 is a perspective view of an electronic time lock
for vault doors or the like showing my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and

FIG. 7 is a bottom plan view thereof.
